UNITED STATES PATENT OFFICE.

JOHN WHITAKER, OF NORTH WALES, PENNSYLVANIA.

PRINTING DEVICE.

1,280,921.

Specification of Letters Patent. Patented Oct. 8, 1918.

Application filed November 20, 1915. Serial No. 62,535.

To all whom it may concern:

Be it known that I, JOHN WHITAKER, a citizen of the United States, and a resident of North Wales, Montgomery county, Pennsylvania, have invented certain Improvements in Printing Devices, of which the following is a specification.

My invention relates to printing devices of the character employed for printing upon checks, notes, drafts, and similar negotiable paper, the amount for which the check, note, draft, etc., is drawn.

The principal object of my invention is to provide a simple, compact, readily operable machine of few parts, cheap to manufacture, and highly efficient in use.

A further object of my invention is to design the machine so that the type lines are disposed diagonally in respect to the feed 20 of the check, or other paper, so that they will be equidistant apart, and one line will underlap the preceding line.

A still further object of the invention is to provide means for cutting or abrading the paper not only at the printed line, but also beyond the line and in the case of a check into the line on which the payee's name is written.

These and other features of my invention are more fully described hereinafter, reference being had to the accompanying drawings, in which:

Figure 1, is a plan view of one form of machine embodying my invention, partly in section on the line I—I, Fig. 2;

Fig. 2, is a sectional elevation on the line II—II, Fig. 1, showing the mechanism in the non-printing position;

Fig. 3, is a similar sectional view; the structure being shown in the act of printing;

Fig. 4, is a plan view of a modified construction within the scope of my invention;

Fig. 5, is a plan view of another construction within the scope of my invention;

Fig. 6, is a view on the line VI—VI, Fig. 1, illustrating a detail of my invention;

Fig. 7, is a plan view of part of the printing drum illustrating a form of type line which I may employ, and

Fig. 8, is a view illustrating a check or similar paper "written" or printed by the machine forming the subject of my invention.

In the structure illustrated in Figs. 1 and 2, I provide a casing 1, a portion of which is set diagonally with respect to a base 2 and at

such an angle with respect to the line of feed of the check as to "write" or print the items representing the amount of the check in a series of lines disposed diagonally across 60 the same with respect to the position of the longitudinal lines usually printed upon check forms and upon which the payee's name and the amount of the check are usually written.

Disposed within this casing is a printing drum or cylinder 3 arranged for substantially vertical depression; such cylinder carrying a series of type lines 4 reading in amounts or items of amounts for which the 70 check may be drawn. These type lines are adapted to coact with a relatively fixed platen 5 suitably mounted and preferably adjustable beneath the base or bed-plate 2, for registry with any one of the printing 75 type lines of said cylinder. The printing drum or cylinder is normally in the raised position so that a check may be readily inserted upon the release of the feed mechanism, and the cylinder having been set in 80 position for the printing of the desired item or amount upon the check or other paper, the depression of a handle 6 connected to said cylinder will lower the same into contact with the check so that the line directly 85 above the platen may be printed upon such check or other paper.

The printing cylinder is mounted upon a shaft or spindle 7, which is journaled in hubs 8 vertically movable in slots 9 formed in the 90 side walls of the casing 1; said hubs having upwardly projecting arms 10 to which are connected links 11; the opposite ends of said 95 links being pivotally mounted upon a rod 12 extending from side to side of the casing.

One hub of the printing drum is attached to a coiled spring 13, which has its opposite end attached to a pin 14 carried by the wall of the casing. The arm 15 of the handle 6 is rigidly connected to one of these hubs; hence 100 downward movement of the said arm will effect the lowering of the printing drum by reason of the link connection; the hubs of said drum following the slots 9 in the side walls of the casing.

For the purpose of inking the type, I provide an inking brush or pad 16 carried by the front wall of the casing, as shown in Figs. 2 and 3, past which the printing cylinder is moved when lowered into and raised 110 from the printing position.

In order that excess ink may be cleaned

from the type face at the printing point just prior to the printing operation, the hubs 8 are provided with arms 17 which are connected to a cross piece 18 extending along the peripheral face of the printing drum and carrying on its inner or upper surface bristles 19 forming a brush adapted to engage the face of the type; such brush being automatically moved away from the printing position when the printing drum is lowered, as shown in Fig. 3.

The form of machine shown in Figs. 1, 2 and 3, is what may be termed a one hand machine; that is to say, the setting of the printing drum or cylinder into proper position as well as the lowering of such cylinder to the printing position may be accomplished by one hand. The printing cylinder is held when set by a finger 20 in substantially the same manner as the cylinder illustrated in my pending application for patent, Serial No. 142,430, filed Jan. 15, 1917, is held, and to this end of the cylinder a setting disk or wheel 21 is secured; the items representing the amounts which may be printed by the drum being disposed diagonally on the peripheral face of the same so as to read in line with the check, as clearly shown in Fig. 1.

30 The printing drum 3 may be set by operating this wheel 21 by hand to the desired printing position; but means for operating the printing drum independently of the wheel 21 may be employed, to wit: a train 35 of gear wheels 22, 23 and 24, internally mounted in the arm 15 of the handle 6 and so arranged that the cylinder may be turned to the desired printing position by rotating the handle 6; said arm and handle being 40 also free for vertical movement to lower said cylinder and effect the desired printing upon the check or other paper. When the printing cylinder is lowered it is guided and held against disarrangement by a lug 25 on the 45 wall of the casting engaging one of the notches or grooves 26 formed in the end of the printing cylinder.

Any suitable feeding means for the check may be employed, and in the drawings I 50 have shown a simple form of device involving an actuating wheel 30 having its engaging surface substantially flush with the bed-plate of the machine and coöperating with a spring-pressed wheel 31 disposed above 55 said bed-plate and engaging the wheel 30 to move in unison therewith and carry the check along. The wheel 30 is mounted on a shaft 32 having a ratchet wheel 33 operated by a pawl 34; said pawl being carried by a lever. 60 35. This lever is connected by a link 36 to an arm 37 projecting from the carrier 18 for the brush 19 and so arranged that the extent of lifting movement thereof will be sufficient to move the check one unit of space 65 each time the printing drum is restored to

its normal position. The wheel 31 may be lifted for the purpose of positioning a check by the lever 38.

Stops 40 to position the check or other paper laterally are preferably provided, being carried by a rod 41, which rod is frictionally held to maintain the stops in the desired position by a spring 42. These stops project above the base 2, which is apertured at 43 for the purpose.

In Fig. 4, I have shown a type of machine in which the handle 6^a and arm 15^a are employed to depress the printing drum only, having nothing to do with the setting device 21^a, disposed at the opposite end of the 80 printing drum and independently operable. The same type of feed device may be employed, and the printing drum of this machine is operated in substantially the same manner as that disclosed in my pending application for patent; the cylinder being journaled eccentrically in hubs 8^a rotatably mounted in the side walls of the casing.

In Fig. 5, however, I show a plan view of another type of machine which, in general 90 characteristics, is more nearly like that forming the subject of my application for patent, filed January 15, 1917, Serial No. 142,430, and in which the printing drum or cylinder 8^b is mounted in the usual way in the frame 95 or casing 1^b and carries type lines 4^b disposed in helical curves and arranged to engage a similarly curved platen so that checks fed in the usual way across the same may have the lines or items of printing diagonally applied thereto. This form of machine is a little more compact than the machine shown in Figs. 1, 2, 3 and 4.

It will be noticed that I may extend the serrated line beyond the line of the type so 105 as to extend across the payee's name on a check and this line may be an inked single line, as shown in Figs. 7 and 8, or may be a double line, as shown in Fig. 1, or any suitable character without departing from the essential 110 features of the invention.

The type indicating the various items or amounts are disposed with their first letters circumferentially in line and by this arrangement I am able to ink portions of the 115 cylinder with inks of different color; the amounts or items thereof being in one color, while the lines extending across the payee's name are in another color.

In some instances the line extending 120 across the payee's name may be scarred and not inked.

By printing the amounts for which the check or other paper is drawn in diagonal lines, it is a simple matter to print or "write" 125 relatively high amounts in the body of the check, and each diagonal line representing an amount, or an item of an amount, or other indicia is spaced equidistant from adjoining lines; the extent of feed of the check 130

after each printing operation being the same. This arrangement greatly simplifies the operation of feeding the check.

The surface of the platen 5 is so made 5 that it will penetrate and open the fibers of the paper and it may act in conjunction with smooth faced type, such as described in Patent No. 1,213,049, Jan. 16, 1917, or the type may have grooves to receive 10 the projecting portions of the platen, as shown in application, Serial No. 56,307, filed October 16, 1915.

Referring to Fig. 8 representing a check, it will be seen that the several impressions 15 are arranged in a line diagonal to the line of the check and the several lines are spaced equidistant apart. I preferably so space the lines that one will underlap another as shown in the drawings, consequently, a check can 20 be written for a suitable amount in a comparatively small space. The particular form of check is set forth in an application filed by me on January 9, 1917, Serial No. 141,390.

25 It will also be noticed that the upright lines of the letters of the check are arranged vertically in respect to the body of the check and this is accomplished by arranging the type on an incline in respect to the cylinder, 30 as clearly shown in Fig. 1. This arrangement makes the words legible. Furthermore, the arrangement of the diagonal lines permits the use of a larger and more legible type than can be used in a machine in which 35 the amount is written on a straight line.

I claim:

1. The combination in a printing device, of a bed; a platen having a serrating face and mounted in the bed and at an angle to 40 the longitudinal line through the bed; a frame overhanging the bed; a horizontally arranged cylinder mounted on the frame and having type and a serrating face; means for turning the cylinder so that a line of 45 type and its serrating face will be brought into alinement with the platen; means for making an impression; and a guide on the bed arranged so that an impression will be

made by the type and platen on a line diagonal to the line of the feed. 50

2. The combination of a base; a guide on the base for guiding a check, or other paper; means for feeding the paper across the base; a serrated platen arranged at an angle in respect to the line of feed; an overhanging frame; a horizontal printing cylinder mounted on the frame and having a series of impression forms consisting of letters and impression lines, the letters and impression lines being arranged so as to aline with the 55 serrated platen; means for inking the letters, the serrations of the several printing lines being at the same end of the line; and means for making an impression so that when an impression is made on a check, the type impression will be on one line and the 60 serrated impression will be on another line. 65

3. The combination of a base; a guide on the base for a check, or like paper, feeding mechanism for feeding a check across the base and in contact with the guide; a platen on the base arranged diagonally in respect to the guide; a printing device located to act in conjunction with the platen to make an impression, said printing device having a 70 series of type lines thereon; and means for adjusting the printing device to bring one character after another in line with the platen. 75

4. The combination in a device for printing amounts on checks and other papers, of a base; a guide on the base; means for feeding a check across the base in contact with the guide; an overhanging frame; a printing cylinder mounted in the frame; means for turning the cylinder; means for causing the cylinder to move to and from the platen, said cylinder having a series of type characters thereon of different denominations, the vertical characters being arranged at 80 right angles to the guide on the base so that as one character after another is printed the individual impressions on the check will be 85 vertical while the line will be inclined. 90

JOHN WHITAKER.
